UNITED STATES PATENT OFFICE.

JAMES NICHOLAS YOUNG, OF NEW YORK, N. Y.

TOILET KIT.

Application filed June 3, 1926. Serial No. 113,512.

The present invention is concerned with the provision of a toilet kit in which a shaving apparatus and other accessories of the toilet may be compactly packaged for purposes of transportation.

An object of the invention is to provide a device of this character in which the various toilet articles will be securely retained in place within a small compact case which may either be carried in the pocket, or tossed carelessly in a traveling bag without danger of injuring the toilet articles or displacing them from their position within the case.

More specifically, an object of the invention is to provide a toilet kit in which conventional types of high grade toilet articles may be compactly assembled as opposed to the various forms of patented kits which make use of unconventional types of razors and other accessories. In other words, I aim to provide a casing for conveniently packing standard high-grade toilet articles, instead of providing inferior unconventional toilet accessories to fit within a peculiarly shaped container.

Further objects of the invention are to provide a device of the character above noted, of simple, practical construction, which will be rugged, durable and efficient in use, neat and attractive in appearance, and which will lend itself readily to the requirements of economical manufacture.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a perspective view of the toilet kit with the cover removed.

Fig. 2 is an enlarged vertical sectional view therethrough showing the toilet accessories in position, and taken on the line 2—2 of Fig. 3.

Fig. 3 is a vertical sectional view on the line 3—3 of Fig. 2.

Fig. 4 is a top plan view of the kit with the cover removed.

Fig. 5 is a transverse sectional view on the line 5—5 of Fig. 2.

Fig. 6 is a bottom plan view of the kit with the bottom removed.

Fig. 7 is an enlarged vertical sectional view through a slightly modified form of kit, taken on the line 7—7 of Fig. 8.

Fig. 8 is a vertical sectional view through the kit of Fig. 7 taken on the staggered line 8—8 of Fig. 7.

Fig. 9 is a top plan view of the kit of Fig. 7 with the cover and the toilet accessories removed.

Referring first to Figures 1 to 6 of the drawings, I have shown an embodiment of the invention which includes a casing 10, open at both ends and of roughly oval shape in cross section. More exactly the wide sides 10^a of the casing are flat and parallel, merging into curved surfaces 10^b which in turn join the ends of the flat narrow parallel sides 10^c. The upper and lower ends of the casing are preferably inwardly offset from the main casing body, so that the upper and lower flanged covers 11, 12 will lie flush with the body when they are slid into place against the shoulders 11^a, 12^a defined by the offset casing ends.

The upper ends of the casing walls 10^c 10^b are cut away leaving a pair of upstanding parallel side walls 13 which are connected at their ends by transverse vertical partitions 14, 15. A horizontal partition 16 lying flush with one cut away end of the casing extends from said end to the partition 14, defining with the members 13, 14 and 15 and the cover 11, when in place, a compartment for the storage of a razor head and blades. This compartment is just large enough to conveniently accommodate the usual backing plate 17, guard plate 18 and blade or blades 19 of a conventional Gillette type razor.

A hole 20 in the end of partition 16 beyond the razor head compartment, is of sufficient diameter to permit the passage of a razor handle shank 21 therethrough, but to stop the enlarged finger knob 22, so that the handle of the razor is hung on the partition and depends therebelow into the casing.

Vertical partition 14 extends for some distance below the horizontal partition 16, and at its lower end connects with a short horizontal partition 23 which in a sense constitutes an offset extension of partition 16. Thus a second deeper compartment is defined adjacent the razor head compartment and this deep pocket or compartment is adapted for the reception of the head 24 of a tooth brush. The brush handle 26 extends

through an opening 25 in partition 23 into the bottom of the casing, so that the brush is in effect suspended on the head, which fits so snugly in its compartment, that any appreciable swinging movement of the handle is prevented.

In the lower corner of the casing under the hole 20, a downwardly facing pocket or compartment for a shaving brush is formed by a short horizontal partition 27 and a vertical partition 28. Preferably the brush 29 stored in this pocket has a relatively short handle 30. The brush is retained in place by the bottom cover 12.

In packing the kit, the toothbrush and razor may be first inserted, the top cover emplaced, and the casing inverted to facilitate the insertion of the shaving brush and a pair of collapsible paste tubes 31, 32 containing toothpaste and shaving cream. One of these tubes is a bit shorter than the other, conveniently fitting in slightly inclined position between the bottom 12 and partition 28, while the other tube fits between the bottom 25 and the partition 16 and leans against the corner of the shaving brush compartment. The diameter of the tubes when filled, is such that they are self sustaining against material lateral displacement. Tubes 31, 32 are preferably slightly skewed as shown to assure a tight fit. Obviously the tubes and shaving brush might be packed first and the tooth brush and razor subsequently entered into their compartments.

In Figs. 7 to 9 I have shown a modified form of kit in which the casing is somewhat more capacious and may carry a comb and a powder container in addition to the other toilet accessories above described.

The construction of this form of container is very similar to the casing of Figures 1 to 6, and similar reference characters have been used wherever possible. The walls 10^b are flat instead of curved. The partition 15 extends the full length of the casing. The partition 16 only spans the space between partition members 14, 15. The partition 27 is near the top of the casing and cooperates with member 15 to provide a short upper shaving brush compartment for a powder container 35 and comb 36.

The compartment for the razor head is longer, so that it may also receive the razor handle and is vertically divided by a number of longitudinally extending partitions 40 which subdivide it into spaces for the head, handle and extra blades. Otherwise the construction and method of packing is the same.

The covers may be provided with suitable means (not shown) for locking them in place, but are preferably snap-fitted over the ends of the casing.

In order to expedite the drying of the tooth brush and shaving brush in the event

that they are placed in the container in a moist condition, it is preferable to provide vent openings 41 arranged above the tooth brush and shaving brush compartments which will permit circulation of air through the container to dry the brushes.

Various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. A toilet kit including a container of elongated cross sectional shape, removable flanged covers for the open top and bottom of the container, opposite sides of the container being cut away at the top to leave a pair of upwardly projecting side walls, vertical transverse cross partitions connecting the ends of said walls, a horizontal cross partition extending from one side of the cut away casing top to the more remote transverse vertical partition and defining with said vertical partitions a razor head compartment.

2. A toilet kit including a container of elongated cross sectional shape, removable flanged covers for the open top and bottom of the container, opposite sides of the container being cut away at the top to leave a pair of upwardly projecting side walls; vertical transverse cross partitions connecting the ends of said walls, a horizontal cross partition extending from one side of the cut away casing top to the more remote transverse vertical partition and defining with said vertical partitions a razor head compartment, the horizontal partition near its end having an opening therein in which a razor handle is adapted to be hung.

3. A toilet kit including a container of elongated cross sectional shape, removable flanged covers for the open top and bottom of the container, opposite sides of the container being cut away at the top to leave a pair of upwardly projecting side walls, vertical transverse cross partitions connecting the ends of said walls, a horizontal cross partition extending from one side of the cut away casing top to the more remote transverse vertical partition and defining with said vertical partitions a razor head compartment, the horizontal partition near its end having an opening therein in which a razor handle is adapted to be hung, one of the vertical transverse partitions extending well below the other and communicating at its lower end with an offset apertured continuation of the horizontal partition, whereby a tooth brush compartment is formed having an opening in its bottom through which the brush handle projects.

4. A kit of the class described including a casing of elongated cross section open at both ends, flanged covers snapping over the ends of the casing and lying flush with the body thereof, the ends of said body being inwardly offset, defining shoulders which constitute abutments for the cover flanges, partition members defining in the upper end of said casing a shallow elongated central razor compartment and a pair of relatively deep compartments at the ends thereof for the purpose specified.

5. A kit of the class described including a casing of elongated cross section open at

both ends, flanged covers snapping over the ends of the casing and lying flush with the body thereof, the ends of said body being inwardly offset, defining shoulders which constitute abutments for the cover flanges, partition members defining in the upper end of said casing a shallow elongated central razor compartment and a pair of relatively deep compartments at the ends thereof for the purpose specified, the outer walls of said latter compartments being cut away to permit manual grasping of their contents when the cover is removed.

JAMES NICHOLAS YOUNG.
